CAMPER'S TOOL

John Le B. Arbuckle, Columbus, Ohio

Application December 16, 1932, Serial No. 647,653

1 Claim. (Cl. 145—62)

This invention relates to improvements in campers' tools, and has for its primary object the provision of an improved combination tool in the form of an ax wherein the handle thereof is provided at one end with a socket for the removable reception of a hunting knife, the construction of the handle being such that it will serve to completely enclose and conceal the knife when the latter is positioned within the socket, so that the ax may be manually wielded in the usual manner without any interference on the part of the encased knife.

It is another object of the invention to construct the ax handle to include a longitudinally extending socket which opens to one end of the handle, the socket being of non-circular form in cross section to conform to the configuration of the knife handle, whereby rotation of the knife when the latter is positioned in the socket will be precluded and accidental removal of the knife from its operative position in the handle prevented.

A further object of the invention rests in providing frictional locking means for positively retaining the knife in its secured position within the handle, whereby to require the application of positive pressures in order to effect the withdrawal of the knife from the handle.

With these and other objects in view, which will appear as the description proceeds, the invention consists in the novel features of construction, combination of elements and arrangements of parts hereinafter fully described and pointed out in the appended claim.

In the accompanying drawing:

Fig. 1 is a perspective view of the improved combination tool comprising the present invention;

Fig. 2 is a longitudinal sectional view taken through the handle of the tool and illustrating the knife in its normal contained position within the ax handle;

Fig. 3 is a horizontal sectional view through the handle, the knife being shown in edge elevation;

Fig. 4 is a transverse vertical sectional view on the plane indicated by the line 4—4 of Fig. 2;

Fig. 5 is a similar view on the line 5—5 of Fig. 3.

Referring more particularly to the drawing, the tool comprising the present invention partakes generally of the form of an ax, such as that used by woodsmen, campers, hunters or the like and comprises the usual metallic head 1 of conventional construction and configuration. Connected with the head 1 is a handle 2 by which the ax

may be grasped and used in a conventional manner. In this instance, however, the ax is provided with a longitudinally extending socket 3, closed at one end and open at its other, and arranged to be removably positioned in the socket 3 is a knife which comprises a handle 4 and an elongated sharpened blade 5. The blade 5 of the knife is received within the inner reduced or restricted portion 6 of the socket 3, while the knife handle 4 is disposed in the enlarged and non-circular outer portion 7 of the socket.

To positively retain the knife in its contained position within the socket 3, the outer end of the handle 2 is provided with a metallic sleeve or ferrule 8, the latter including a flange 9 disposed within the open end portion of the socket 3. The knife handle 4, as shown in Fig. 5, is provided with a transversely disposed opening in which is positioned a metallic casing 10, the latter being adapted to receive a small coil spring 11, which normally tends to force a metallic ball outwardly to the limit of its movement as afforded by the beaded end of the casing 10. Normally, the ball 12 projects a slight distance beyond the side of the knife handle. By this construction, when the knife is positioned in the socket, as shown in Fig. 3, the ball 12 will engage with a shoulder produced by the end of the flange 9, which produces a friction-lock by which the knife is positively retained within the socket of the ax handle and accidental removal thereof precluded. If desired, the extreme outer end of the knife handle 4 may be equipped with a knob 13 to facilitate the withdrawal of the knife from its applied position within the ax handle.

In view of the foregoing, it will be seen that the present invention provides a convenient and compact combination tool particularly adapted for the needs of campers or for out-of-door purposes generally. In such pursuits, it is often necessary or convenient to use both a knife and an ax and where these tools are provided separately, one or the other is often missing. By combining the same in a single unit, however, this disadvantage is avoided. It will be understood that the ax handle may be formed from any suitable material or of any desired configuration and general dimensions. Due to the provision of the restricted portion 6 of the socket, which receives the knife blade, the cross sectional area of said socket is comparatively small in regions where the ax handle tapers to a point of its smallest diameter. This feature prevents the presence of the socket from weakening the handle or caus-

ing it to split or break when used in the ordinary manner.

While I have described what I consider to be the preferred form of my invention, nevertheless it will be appreciated that its constructional details are subject to some considerable modification and variation without departing from the essential features of the invention, as the latter are defined in the appended claim.

10. What is claimed is:

In a combination tool, a handle provided with a longitudinally extending socket opening to one end thereof, the inner part of said socket being of restricted slot-like formation and the outer portion of said socket towards the end of the handle being of enlarged or greater cross sectional area, the said socket providing shoulders substantially midway of its length at the points of juncture of the restricted slot-like inner portion with the enlarged outer portion thereof, a knife provided with a blade and handle remov-

ably positioned in said socket with the blade of the knife received in the restricted slot-like portion of the socket and the handle of the knife in the enlarged outer portion thereof, the end of the knife handle adjoining said blade being engaged with said shoulders to control the inserted positions of the knife within said socket, a metallic ferrule reenforcing the end of the tool handle adjacent to the open end of said socket, said ferrule being provided with a flange arranged in 10 the socket contiguous to its open end, said flange being formed with a shoulder, and a spring-pressed member carried by the knife handle and arranged to engage with the walls of said last-named shoulder when the knife is positioned within said socket to positively retain said knife within said socket, said knife being confined against accidental movement when positioned within said socket.
